(57) **CLAIM**

The ornamental design for a portable electronic computer for coordinate input device, as shown and described.

DESCRIPTION

FIG. 1 is a top-front perspective view of a portable electronic computer for coordinate input device according to my new design;

FIG. 2 is a top-rear perspective view thereof;

FIG. 3 is a bottom-front perspective view thereof;

FIG. 4 is a top plan view thereof;

FIG. 5 is a bottom plan view thereof;

FIG. 6 is a front elevational view thereof;

FIG. 7 is a rear elevational view thereof;

FIG. 8 is a left side elevational view thereof; and,

FIG. 9 is a right side elevational view thereof.

The dashed broken lines in the drawings show portions of the portable electronic computer for coordinate input device that form no part of the claimed design.
